UNITED STATES PATENT OFFICE

KARL DANTHINE, OF BERN, SWITZERLAND, ASSIGNOR TO HEINRICH SURBER, OF ZURICH, SWITZERLAND

RIFLE ATTACHMENT FOR FIRING MINIATURE AMMUNITION

Application filed December 1, 1928, Serial No. 322,992, and in Switzerland December 8, 1927.

This invention relates to an auxiliary device for firing of small calibre ammunition from rifles, and has reference particularly to an auxiliary barrel, which is supported directly in front of the muzzle end of the rifle and which has its bore of any desired calibre and entirely independent of the bore of the rifle itself.

In connection with the well known devices 10 of this character, the auxiliary barrel receiving the small calibre ammunition is introduced directly into the inside of the rifle barrel. The modern army firearm is a small calibre rifle and as a consequence, when it 15 is required to insert the auxiliary barrel inside the rifle bore, the auxiliary barrel is only able to handle small calibre ammunition with percussion caps, and not cartridges with powder charge, for the reason that there 20 might be the danger of the very thin walled auxiliary barrel becoming deformed, under pressure of the charge. The well known devices, as a result, may not be used for small cartridges having a range of more than 200 25 meters in the open.

With the foregoing in mind, it is the purpose of this invention to provide means whereby small calibre ammunition of any diameter may be used irrespective of the size 30 of the rifle bore.

In the accompanying drawing is illustrated by way of example one form of construction according to the present invention.

Figure 1 shows a longitudinal section 35 wherein only so much of the army rifle is illustrated as is necessary for explaining the invention, and

Figure 2 shows a detail.

The device is provided, for the purpose of 40 connecting the auxiliary barrel 1 to the barrel 2, with a member 3 formed as a sleeve which fits into a ring 4, fitted over the front end of the rifle barrel, and has its reduced extension 5 fitted into the rifle barrel. The 45 auxiliary barrel 1 and the sleeve 3 are connected together by means of a bayonet joint 17. The cartridge seating of the auxiliary barrel 1 is indicated at 16. The ring 4 is provided with a downwardly projecting 50 forked arm 6 (Figure 2), which is secured

or rigidly connected to a fixed part of the rifle, for example the upper band 8, by a bolt 7, the upper band 8 being secured to the rifle stock in any suitable manner. In this manner the sleeve 3 is securely attached to the rifle barrel. The sleeve 3 accommodates at its rear end in a boring thereof a cylindrical sleeve 9 in which a cylindrical head 10 is longitudinally movable, this head being provided with two projecting striker pins 11 passing through two holes in the bottom of the sleeve 9, these striker pins serving to ignite the cap of the miniature ammunition fitted into the cartridge seating 16. In the smaller boring of the extension 5 and in a 60 guide sleeve 12 fitted into the cartridge seating of the rifle barrel 2, there is slidably guided a rod 13. A spiral spring 14 fitted around the rod 13 bears at the front on the extension 5 and at the rear against a collar 70 15 of the rod 13 whereby the latter is always moved rearwardly within reach of the striker 18 of the rifle.

When a blow is imparted to the rod 13 by the striker 18 of the rifle this is transmitted 75 by the rod 13 to the striker 10 which in turn by means of the pins 11 acts upon the cap of the miniature ammunition. The spring 14 then immediately returns the rod 13 into its initial position ready for the next shot. For 80 removal of the cartridge case from the auxiliary barrel 1 and for loading this with a fresh cartridge the auxiliary barrel must be removed from the sleeve 3 by disengaging the bayonet joint 17. For this purpose the rifle is placed on its butt end. During this 85 operation the striker device 10, 11 returns to its initial position under the action of gravity.

Into the sleeve 3 may be fitted auxiliary 90 barrels of different caliber and length according to the ammunition to be used and according as to whether firing is to take place in the open or in closed spaces. The device described may be applied to any suitable 95 army rifle, which after the removal of the device can immediately be used for its normal operation. Damage to the rifle barrel when using the device, forming the subject 100 of the invention, is practically excluded.

Instead of being attached to the upper band 8 by means of the bolt 7 the sleeve 3 could also be attached to the rifle barrel 2 by other suitable securing means.

What I claim is:-

5. 1. A device for firing miniature ammunition with army rifles comprising an auxiliary barrel, into which the miniature ammunition is adapted to be placed, said auxiliary barrel extending in its entirety beyond the end of the rifle barrel and having a sleeve shaped member bearing closely against the end of the rifle barrel and fitting snugly into the latter, said member serving to effect the connection between the rifle barrel and the auxiliary barrel, a striking device, and a rod fitted into the rifle barrel in such a manner, that the movement of the striker of the rifle is transmitted to the rod and by means of the striking device is transmitted to the miniature ammunition for the purpose of firing the latter.
10. 2. A device for firing miniature ammunition with army rifles comprising an auxiliary barrel, into which the miniature ammunition is adapted to be placed, a sleeve shaped member adapted to be fitted on the front of the rifle barrel, this member serving to effect the connection between the rifle barrel and the auxiliary barrel, a sleeve firmly mounted in said connecting member, a striking device guided in this firmly mounted sleeve, and a rod fitted into the rifle barrel in such a manner, that the movement of the striker of the rifle is transmitted to the rod and by means of the striking device is transmitted to the miniature ammunition for the purpose of firing this, said striking device being arranged in such a manner, that when placing the rifle on its butt end the striking device returns to its initial position under the action of gravity.
15. 3. A device for firing small calibre ammunition from rifles, comprising an auxiliary barrel disposed co-axially of the rifle barrel and having its bore independent of and beginning beyond the end of the rifle barrel, said auxiliary barrel extending in its entirety beyond the end of the rifle barrel, and means operatively associated with the rifle for firing ammunition from said auxiliary barrel.
20. 4. A device for firing small calibre ammunition from rifles, comprising an auxiliary barrel disposed co-axially of the rifle barrel and extending in its entirety beyond the end of the rifle barrel, and means insertible in the bore of the rifle barrel to support the said auxiliary barrel beyond the end of the rifle barrel.
25. 5. In combination with a rifle having a bored barrel and firing mechanism therefor, of an auxiliary device for firing small calibre ammunition from said rifle, comprising a barrel disposed coaxially of the rifle barrel and entirely beyond the end of the latter,

means insertable at one end in the nozzle end of the rifle barrel and embracing the auxiliary barrel at the other end, and striker means in the inner end of the auxiliary barrel and operatively connected with the firing mechanism of the rifle for firing ammunition from said auxiliary barrel.

6. In combination with a rifle having a bored barrel and firing mechanism therefor, of an auxiliary device for firing small calibre ammunition from said rifle, comprising a barrel disposed co-axially of the rifle barrel, a firing means between the rifle and auxiliary barrels, a union for the two barrels, comprising a socket to receive the firing means and aid the auxiliary barrel and support the latter beyond the end of the rifle barrel and a reduced portion to fit tightly in the muzzle end of the rifle barrel, and an axially reciprocal rod mounted in the rifle barrel and projecting through the reduced portion of the union at one end to operate the firing means and connected to the firing mechanism of the rifle barrel at the other end.

7. A union for a rifle and auxiliary barrel, as claimed in claim 6, including a bayonet joint between the free end of the socket and the auxiliary.

8. A union for a rifle and auxiliary barrel, as claimed in claim 6, including a pair of circular bands embracing the end of the rifle barrel and socket and the stock of the rifle, and a connection between the two bands.

9. An auxiliary device, as claimed in claim 6, in which the firing means comprises a cap, a firing head therefor, and firing pins carried by the cap and movable under contact of the head, the latter being disposed in the path of movement of said rod connected with the firing mechanism of the rifle.

In testimony whereof I affix my signature.

KARL DANTHINE.
